UNITED STATES PATENT OFFICE

171,891

CHAIR

Bertis F. Hamilton, Columbus, Ind.

Application August 2, 1952, Serial No. 20,881

Term of patent 14 years

(Cl. D15--8)

To all whom it may concern:

Be it known that I, Bertis F. Hamilton, a citizen of the United States, residing at Columbus, county of Bartholomew, State of Indiana, have invented a new, original, and ornamental Design for a Chair, of which the following is a specification, reference being had to the accompanying drawings, forming a part hereof.

Fig. 1 is a front elevation of a chair showing my new design;

Fig. 2 is a plan view of the chair; and

Fig. 3 is a side elevation of the chair.

I claim:

The ornamental design for a chair, as shown.
